UNITED STATES PATENT OFFICE.

T. F. TAFT, OF WORCESTER, MASSACHUSETTS, ASSIGNOR TO HIMSELF, A. P. BROWN, AND
WM. M. PAGE.

SHEAR AND PUNCH.

Specification of Letters Patent No. 31,835, dated March 26, 1861.

To all whom it may concern:

Be it known that I, T. F. TAFT, of the city and county of Worcester, in the State of Massachusetts, have invented a certain useful and Improved Article of Manufacture, which I denominate "Taft's Improved Combined Shear and Punch;" and I do hereby declare that the following is a full, clear, and exact description of the same, reference being had to the accompanying drawings, which form a part of this specification, and in which—

Figure 1, represents a front view of the machine, and Figs. 2, 3, and 4 represent detached sections on a reduced scale.

It has always been a desideratum to obtain a machine to be used in machine shops, and by general iron workers, which should possess the combined advantages of a good shear and punch, while at the same time the expense and frame work should not much exceed the cost and size of ordinary single machine, and be at the same time capable of independent and simultaneous action.

To accomplish the above, I first make a frame having a base A. from one side of the rear of which projects a curved neck B. which supports the forwardly projecting parts marked C. D. and F'. The above parts are all cast in one piece.

Through the top of the part marked C. and D. is a common hole f, while the interior of the parts are cored out as indicated at g, Fig. 3, which is a view of the part C. looking in the direction of arrow 1, Fig. 1, as it appears when the cap E. shaft d, and link piece E'', are removed.

Within the part C. works a slide piece G. the lower outer side of which is grooved out so as to receive the upper part of knife h, which is bolted thereto by screw bolts as indicated in Fig. 3, so that its outer surface will be flush with the outer surface of the slide G. The upper part of the slide G. is also grooved or cored out as seen at 1, while a pin 2, projects out from the upper part of the slide G. so that when the cap E. is fastened on by bolts E'. the end of shaft d, as seen in Fig. 2, will enter the hole f, while the hole in the lower end of the link piece E''. will be entered by the pin 2, in the slide G. so that as the shaft d, is operated by lever c, in the piece b, (the latter being fastened to the end of shaft d,) the slide G. and shear h, will have a reciprocating motion im-

parted to them in consequence of the upper end of the link E''. working on the eccentric d'', on the shaft d, whereby the shear h, will be caused to work up and down against the right side of the stationary shear h' which is bolted to the base A. as indicated in Figs. 1 and 3. The cap piece E. is cut out at e, to facilitate the attachment or removal of the shear h.

The punch H. is attached to the lower end 65 of slide G', which works in a recess in the part D. and is operated by a link similar to E''. which passes over an eccentric on the inner end of shaft d', which is held in place by cap piece E. bolted to D. by bolts D'. so 70 that as the lever c', is moved (the part b' being fastened to shaft d',) the punch has a reciprocating motion imparted to it, whereby its lower end is caused to work down into a die in the part I'. of the part I. which is 75 bolted to the upper side of the shelf F'. by bolts k.

By unscrewing the set screws m, the die can be removed and one of a different shape and size be inserted, while the punch can 80 be changed by unscrewing set screw n.

The slide G'. is cast with a projection g', so as to allow of the punch being inserted as far out from the frame as possible. The cap E. is recessed as at e', to permit the projection g', to work up and down freely.

j, is a spring or guard to free the point of the punch when it rises.

The shelf F'. is strengthened by having ribs F''. cast underneath. 90

When desired for lightness, the recesses in the parts C. and D. may approach quite near each other—projections f', on each side of the thin web, being left to give proper bearings to the inner ends of the shafts d, d', 95 which abut against each other.

Fig. 4, is a side view of the parts C. and D. and a part of neck B. looking in the direction of arrow 2, Fig. 1.

The hole in the piece I'. for the punch die, 100 is round, so that the exterior of all dies can be of the same shape and size.

The part punched out drops down through a hole in the shelf or table F'.

The parts a, a', cast on the cap pieces E. 105 F. afford suitable bearing surface for the outer edges of shafts d, d'.

In operating the shear, instead of a lever, a pulley could be attached to the end of shaft d, and a continuous rotary motion com- 110

municated to said shaft by means of a belt. In this case a uniform reciprocating motion would be communicated to shear h , through eccentric d'' , link E'' , and slide piece G .

5 The punch could be operated in the same way.

When operated by hand no inconvenience is experienced from one operator interfering with the other; since one handle can be operated backward while the other is operated forward. Then again, a strip can be cut by the shears from a plate or sheet of iron of any required length, since the sheet passes in a straight line to the left of the neck B . 10 15 while the part cut off is deflected and passes under said neck. Holes are to be made in the parts marked C . and D . for oiling the bearings of the shafts and eccentrics.

Owing to the compact and simple construction of the above machine, it can be af- 20

forded at a cost that will enable any blacksmith to have one, whereby much of the hard labor and expense attending his profession is obviated.

As an article of general utility, its merits 25 are too apparent to require enumeration.

Having described my invention, what I claim and desire to secure by Letters Patent, as an improved article of manufacture, is:—

30 A combined shear and punch, in which the parts A . B . C . D . and F' . are all cast in one piece, in combination with coring out the parts C . and D . substantially as described.

In witness whereof I have hereunto subscribed my name.

T. F. TAFT.

In presence of—

JAMES H. BANCROFT,
O. P. RICHARDSON.
